FIG. 1.

FIG. 2.

Inventor:
Herbert R. Hanley
by *Alfred S. Davis*
His Attorney.

UNITED STATES PATENT OFFICE.

HERBERT R. HANLEY, OF WINTHROP, CALIFORNIA, ASSIGNOR TO BULLY HILL COPPER
MINING & SMELTING COMPANY, A CORPORATION OF NEW JERSEY.

ELECTROLYTIC APPARATUS.

1,241,967.

Specification of Letters Patent.

Patented Oct. 2, 1917.

Application filed June 5, 1916. Serial No. 101,725.

To all whom it may concern:

Be it known that I, HERBERT R. HANLEY, a citizen of the United States, residing at Winthrop, in the county of Shasta, State of California, have invented certain new and useful Improvements in Electrolytic Apparatus, of which the following is a specification.

The present invention comprises an apparatus for the electrolytic deposition of metal and particularly the electrolysis of zinc from aqueous solutions.

When a metal, such for example, as zinc is electrolyzed from a solution of zinc sulfate, zinc chlorid or the like, the electrolyzing voltage rises after a period of time due to polarization and the deposit also becomes pitted and uneven. By forcing air or other suitable gas into the apparatus into contact with the cathode gas bubbles are brushed from the cathode and polarization is diminished making it possible to secure thicker and more even deposits of electrolyzed metal.

My invention comprises a novel form of apparatus for introducing air into an electrolytic cell, the aerating device serving also as anode. In accordance with one of the features of my invention the air is introduced into the electrolyte through an opening so large that clogging is avoided, the air being received from a supply pipe through a non-submerged orifice of smaller diameter than the submerged orifice.

In the accompanying drawing Figure 1 is a sectional view of a cathode plate and two anode elements and Fig. 2 is a sectional view of one end of a cell.

Referring to the drawing, the cell as shown in Fig. 2 comprises a tank or receptacle 1 containing the solution to be electrolyzed, for example, zinc sulfate, in which are located a cathode 2 consisting of aluminum, or zinc, and a number of vertical anode pipes 3. The anode pipes which may consist of lead, each communicates at the top with a horizontal air supply pipe 4 through an orifice 5 about $\frac{1}{4}$ " in size, the dimension of this orifice being adapted to the drop in air pressure desired from the pipe 4 to the pipes 3. The pipe 4 communicates through a valve 6 with an air main 7. The lower end of the anode pipes 3 communicates with a hollow base 8 of suitable insulating material, for example, wood or porcelain.

A tight fit may be produced by the use of an acid-resisting cement 8', for example, sulfur. The openings 9 in this base may have a diameter of about $\frac{3}{8}$ " or larger, so that the opening will not be clogged by crystallized salts or foreign matter. The cathode is maintained in alinement and the course of the bubbles upward is directed by the guides 10 to cause the bubbles to impinge on the cathode surface.

The air bubbles passing over the cathode 2 sweep away adhering hydrogen bubbles. As indicated by the dotted lines in Fig. 1 and also in Fig. 2, the alternate holes 9' communicate with the electrolyte on the side opposite the alternate holes 9, and the holes 9 of adjacent anode bases are located opposite each other. The rows of anode pipes are all connected in parallel through the air supply pipe 4, each set, if desired being insulated from the air main by a section 11 of rubber or the like.

What I claim as new and desire to secure by Letters Patent of the United States, is:—

1. An aerating device, comprising a receptacle containing a liquid, an air supply pipe, one or more pipes communicating therewith through a non-submerged orifice, said pipes having a submerged orifice of larger diameter than said non-submerged orifice.

2. An electrolytic apparatus comprising a receptacle, an electrolyte therein, a cathode, anodes located on opposite sides of said cathode, each of said anodes having a plurality of openings submerged in said electrolyte, pipes communicating with said openings, and a conduit communicating with each of said pipes through non-submerged openings of smaller size than said submerged openings.

3. An electrolytic apparatus comprising a receptacle, an electrolyte therein, a cathode, an anode located adjacent said cathode comprising a plurality of pipes, a hollow base having a plurality of openings, located near the bottom of said cathode and communicating with said pipes and a conduit supplying said pipes through non-submerged openings of smaller size than the openings in said anode base.

4. An electrolytic apparatus comprising a receptacle, an electrolyte therein, a cathode plate, a row of pipes located on opposite sides of said cathode, each constituting an

anode, each of said pipes having a non-submerged constricted opening, an air supply pipe communicating with said anode pipes through said constricted openings, 5 submerged bases common to each row of anode pipes having openings communicating with said pipes of larger diameter than said constricted openings, openings in opposite bases being located opposite each 10 other.

5. An electrolytic cell comprising a receptacle, an electrolyte therein, a cathode,

a hollow anode having a plurality of openings submerged in the electrolyte, and terminating near the lower part of said cathode, means for supplying a gas to said anode to brush adhering gas bubbles from said cathode, and means for guiding the ascending bubbles to impinge on the cathode surface.

In witness whereof, I have hereunto set my hand this twenty-second day of May, 1916.

HERBERT R. HANLEY.
